A. C. BARKER

ATTACHMENT FOR GARMENT HANGERS

Filed June 6, 1922

Inventor.
Alice C. Barker
By Roberts, Roberts & Cushman
Atty's.

UNITED STATES PATENT OFFICE.

ALICE C. BARKER, OF ALLSTON, BOSTON, MASSACHUSETTS.

ATTACHMENT FOR GARMENT HANGERS.

Application filed June 6, 1922. Serial No. 566,308.

To all whom it may concern:

Be it known that I, ALICE C. BARKER, a citizen of the United States of America, and resident of Allston, Boston, in the county of 5 Suffolk and State of Massachusetts, have invented new and useful Improvements in Attachments for Garment Hangers, of which the following is a specification.

Garment hangers in common use are not 10 adapted to securely retain garments thereon. Even when carefully hung thereon garments frequently slide off and fall to the floor where they become mussed and soiled. This defect causes considerable losses to 15 tail stores selling clothing, since the soiled garments often have to be sold at a reduction. Moreover the ease with which a garment may be slipped from a hanger is no small factor in the successful operations of 20 shoplifters.

Objects of the invention are to prevent garments from readily slipping from hangers, to interfere with the hasty removal of garments from hangers by unauthorized 25 persons, to construct an attachment for hangers which will secure the above objects, which is inexpensive to manufacture, and which can be quickly applied to existing hangers without making changes therein, 30 and in general to remedy the defects of the ordinary garment hanger.

For the purpose of illustrating the invention one concrete embodiment thereof is shown in the accompanying drawings, in 35 which:

Fig. 1 is a side elevational view;

Fig. 2 is a view similar to Fig. 1 showing the attachment on a different form of hanger;

Fig. 3 is a plan view from Fig. 2;

Fig. 4 is a side elevational view showing the device in use.

The embodiment of the invention shown for the purpose of illustration is disclosed 45 as adapted to garment hangers in common use such as the hanger A shown in Fig. 1 having diverging arms *a* and *a'* and a hook *a*² or the hanger B shown in Fig. 2 having diverging arms *b* and *b'* and a hook *b*². 50 The invention comprises strips 5 and 6 of flexible material preferably fabric such as webbing or tape, which is relatively non-elastic, attached to the arms *a* and *a'* or *b* and *b'* adjacent their ends in any suitable

manner. The free ends of the strip are provided with suitable fastening means such as a snap fastener, the socket 7 of which is attached to one of the strips as strip 5 and the ball section to the other strip as strip 6. The strips are shown hanging loose in Fig. 1 and 60 as fastened together in Fig. 2, thereby making a flexible connection between the diverging arms of the hanger.

In its preferred form the attachment comprises a relatively long strip or strap 9 of 65 flexible material such as webbing or tape, the free ends of which form the strips 5 and 6 previously described. The means for fastening the strip on the hanger may comprise an eyeleted opening or hole 10 in the webbing 70 through which hook *a*² or *b*² of the hanger passes, hole 10 then being disposed around the shank of the hook adjacent the top of the hanger as shown in Figs. 1, 2, and 3. From 75 the hook the strip extends along the top of arms *a* and *a'* or *b* and *b'*, as shown, and is securely held thereon adjacent the arms by bands or loops of elastic material stitched or otherwise fastened thereto, the elastic bands being slipped over the free ends of 80 the arms of the hanger in an obvious manner. The fabric strip 9 covering the smooth upper surface of the diverging arms of the hanger offers frictional resistance to the 85 slipping of a garment when the device is in use.

Fig. 4 illustrates the method of using a hanger provided with the attachment herein disclosed. The free ends 5 and 6 of the attachment pass through the arm holes of 90 the garment and are fastened together at the back thereof by the fastening means such as the snap fastener 7, 8. The flexible connection thus made by strips 5 and 6 across 95 the back of the garment between the arms 100 does not detract in any way from the appearance of the garment as seen from the front, and securely holds the garment against accidental movement thereof and interferes with the removal therefrom by unauthorized 105 persons. Moreover, the frictional resistance afforded by the strip 9 across the top of the hanger tends to retain the garment as first arranged on the hanger, and prevents it from slipping to one side or the other so as to hang in an unsightly manner. Since no nails, tacks, pins or similar metal parts are used about the attachment there is nothing

2
to tear or otherwise injure the garments hung thereon. In the case of garments having long sleeves strips 5 and 6 are passed under the lining or through any convenient openings before being fastened together.

I claim:

1. The combination with a garment hanger having diverging arms, of a strip of flexible material upon the upper surface of said arms 10 to oppose frictional resistance to the slipping movement of a garment along said arms, the ends of said strip being of a length to permit them to be fastened together to form a flexible connection between 15 the arms to securely retain a garment thereon.
2. The combination with a garment hanger having a supporting hook and arms diverging therefrom, of a fabric strip disposed 20 upon said arms, and means including members of elastic material encircling the arms to retain the strip upon the hanger, the ends of said strip having fastening means whereby said ends may be fastened together to

form a flexible connection between said arms 25 to securely hold a garment thereon.

3. An attachment for garment hangers comprising a fabric strip adapted to be attached to a hanger along the upper surface thereof, the attaching means including a 30 hole in the strip through which the shank of the hook extends, and fastening means on the ends of the strip adapting the latter to be fastened together to form a flexible connection across the hanger to hold a garment 35 thereon.

4. An attachment for garment hangers comprising a strap adapted to extend between the opposite arms of the hanger, and means for attaching the strap to the hanger 40 comprising loops encircling the arms thereof and an opening through which the hook on the hanger may extend, the strap having a detachable fastener whereby it may be opened 45 to receive a garment.

Signed by me at Boston, Massachusetts,
this second day of June 1922.

ALICE C. BARKER.
